UNITED STATES PATENT OFFICE

1,986,527

SWITCH FOR ELECTRICALLY CONTROLLED SIGNALS

Reinhold R. Rach and William E. Rach,
Detroit, Mich.

Application February 26, 1934, Serial No. 712,935

2 Claims. (Cl. 200—168)

Our invention relates to electric switches and a case therefor and has for its general object the provision of a means whereby the switch is operated by a sliding motion of the operating button 5 and a specially designed spring that will form contact for closing either of the two circuits co-ordinated with the switch.

While this switch is readily applicable to any phase of the electrical art, in designing the switch 10 our primary intention is to provide one that is particularly adapted to our combination electric right and left turn, stop and tail light signal, the application for patent for same being filed simultaneous with this application.

It will become obvious that the invention possesses further advantages, clearly disclosed during the course of the following detailed description, illustrated throughout the accompanying drawing, and more specifically pointed out in the 15 appended claims.

With reference to the drawing:

Figure 1 is a longitudinal section of the complete invention through the center thereof.

Figure 2 is a top plan view of the invention 25 with terminal and switch connecting nuts omitted and partly broken away so as to expose a part of the interior thereof.

Figure 3 is a front elevation of the switch, showing the same normally secured to a support 30 and ready for use.

Figure 4 is an elevation of the face plate of the invention.

Figure 5 is a greatly reduced top plan view of the principal actuating member of the invention.

Figure 6 is a sectional view taken substantially upon line 6—6 of Figure 1.

Figure 7 is an isometric view of a portion of the top insulating member of the invention.

The invention comprises an elongated metallic 40 case having bottom 1, sides 2 and ends 3, and the top thereof open as clearly indicated in Figures 1 and 6.

With particular reference to Figure 1 it is observed that the top of said case is completely 45 enclosed by plate 4, which is of the formation as indicated and is composed of a suitable insulating material referring to Figures 1 and 7, it is clear that transversely extending recesses 5 are provided for the respective ends of plate 4 which 50 are adapted to receive the similar formed portion 6 of the metallic case. Lugs 7 are provided on the plate 4 where shown and each of said lugs has a threaded aperture for the reception of screw 8, which passes through ends 3 respectively.

55 In this manner recesses 5 prevent pivoting of

plate 1 relative to the metallic case and screws 8 rigidly holding the plate to the case in the position as shown in Figure 1.

The contact actuating member includes a central cam portion 9 and elongated flat end portions 10. The free corners of the cam portion are rounded as at 12 and normally, the free ends of the leaf spring 13, constituting the movable contact extend over the rounded corners of the cam portion thus holding the actuating member 10 against accidental sliding movement. The free ends of the spring contact element 13 engage the respective flat end portions 10, thereby holding the slidable actuating member against the base of the casing. A button 11 extends forwardly 15 from the outer face of the slidable member for facilitating the actuation of said member.

Spring 13 is secured where shown, to plate 4 by screw 14 with the usual nut, lock nut and washer. Said screw also forming an electric terminal 20 and likewise secured to wire A. Similar screws 15 and 16 are provided in spaced apart relation and secured to plate 4 where indicated. Screw 15 having wire B secured thereto and screw 16 being connected to wire C. The customary nuts and 25 washers for screws 15 and 16 are clearly visible.

Face plate 17 is employed and is secured to the metallic case by means of screws 18 and through preferably instrument panel D of an automobile. 30 The usual nuts and washers for screws 18 are obvious.

In Figure 4 it is seen that rectangular slot 19 is provided within plate 17, and button 11 of member 9 slidably projects through said slot as in 35 Figure 1. When button 11 is slidably moved to the dotted position of 11A it is seen that the adjacent end of spring 13 is moved to the dotted position 13A and accordingly contacts screw 16 which closes an electric circuit, or a circuit co-ordinated with the right turn signal of an automobile signalling device, and likewise when button 11 is moved to the dotted position of 11B the adjacent end of spring 13 is moved to the dotted position of 13B and likewise contacts screw 15 45 and closes an electric circuit, or a circuit co-ordinated with the left turn signal of an automobile signalling device.

It will be observed that regardless of the position of the slidable actuating member, a portion 50 of the contact spring 13 will be in engagement with the actuating member, urging the same outwardly against the base of the casing and thus preventing any rattling of any of the movable parts of the switch.

- It will also be noted that sides 2 of the metallic case are reduced and extended as at 20, which are for the purpose of forming a guide for the sliding motion of the elongated end members 10. 5 Also openings 21 are provided in ends 3 of the metallic case respectively, for free passage of ends 10 of member 9 during any normal operation of the device.

10 It is further understood that the switch may be employed in any device or arrangement where an electric switch is required, as well as being specially designed for an automobile signalling device.

15 Having thus described our invention, what we claim as new is:

1. In an electric switch, a casing open at its top, an insulating plate secured in said open top, stationary contacts carried by the insulating plate, a convex contact spring arranged in the casing and secured at its intermediate portion to the insulating plate, the ends of the contact spring being normally out of contact with the respective stationary contacts, an actuating member 20 slidable in the casing and including a central cam portion and elongated end portions, said contact spring normally extending over the cam portion and engaging the respective end portions of the actuating member to hold the same against the adjacent wall of the casing, a button projecting outwardly from the actuating member through the base of the casing for sliding said actuating member to selectively move the ends of the contact spring into engagement with the stationary contacts, the end walls of the casing having openings to permit the elongated 25 portions of the actuating member to slide therethrough, and reduced extensions formed on the side walls of the casing for receiving and guiding the respective elongated end portions, said side wall extensions projecting beyond the ends of 30 the casing.

tions of the actuating member during the sliding movement of the latter.

2. In an electric switch, a metallic casing including a base, side and end walls, an insulating plate for disposition in the open top of the casing, apertured lugs depending from the ends of the insulating plate, fastening screws extending through the end walls of the casing and threaded into the respective lugs, the upper face of the insulating plate being cut away at each end, the upper edge of each end wall being disposed laterally to engage the respective cut away portion of the insulating plate, stationary contacts carried by the insulating plate, a convex spring arranged in the casing and secured at its intermediate portion to the insulating plate, the ends of the contact spring being normally out of contact with the respective stationary contacts, an actuating member 20 slidable in the casing and including a central cam portion and elongated end portions, said contact spring normally extending over the cam portion and engaging the respective end portions of the actuating member to hold the same against the adjacent wall of the casing, a button projecting outwardly from the actuating member through the base of the casing for sliding said actuating member to selectively move the ends of the contact spring into engagement with the stationary contacts, the end walls of the casing having openings to permit the elongated 25 portions of the actuating member to slide therethrough, and reduced extensions formed on the side walls of the casing for receiving and guiding the respective elongated end portions, said side wall extensions projecting beyond the ends of 30 the casing.

REINHOLD R. RACH,
WILLIAM E. RACH.
